UNITED STATES PATENT OFFICE.

FRITZ WILHELM OTTO BOECKEM, OF LONDON, ENGLAND, ASSIGNOR TO ARTHUR MORRIS, OF REIGATE, ENGLAND.

CARBURETING APPARATUS.

1,214,885.

Specification of Letters Patent.

Patented Feb. 6, 1917.

Application filed March 5, 1914. Serial No. 822,732.

To all whom it may concern:

Be it known that I, FRITZ WILHELM OTTO BOECKEM, a subject of the King of Great Britain, residing at 30, 31, and 32 Bolsover street, Great Portland street, London, W., England, have invented certain new and useful Improvements in or Relating to Carbureting Apparatus, of which the following is a specification.

10 The present invention relates to apparatus for use in the production of carbureted air, of the automatic type wherein a volatile hydrocarbon, such as petrol, is supplied with air automatically, according to gas 15 consumption, to a carbureting or mixing chamber, in which a pump or other charging device working in water takes up the mixture and forces it into a bell or reservoir from whence it is drawn off, as required, for use.

In such apparatus although the supply of air and gas to the carbureter is regulated and controlled according to the gas consumption, it is found that the pressure and 25 richness of mixture within the carbureter varies, according to whether the gas is being drawn off quickly or otherwise, or from any other causes, as owing to the variation in pressure the water level in the pump device also varies. Consequently the free 30 space above the water, in which the mixture of air and gas takes place, also varies, thus causing the richness of the mixture to vary with the variation in water level.

35 Now as it is most desirable that the mixture should, throughout be as constant as possible, it is desirable that this variation in water level should be prevented, or in other words, that the water should be maintained 40 at as near a uniform level as possible. This I effect by providing an overflow chamber or compartment into which some of the water in the pump chamber will be driven when the gas pressure exceeds the normal 45 and from which it is automatically returned to the drum chamber, so as to maintain as nearly as possible a constant water level irrespective of pressure in the chamber.

50 Various means may be employed to effect this equalization of water level, one of which will be described in detail, in connection with a gas generator of the type described, reference being had to the accompanying drawings.

Figure 1 is an elevation, partly in section 55 of a carbureter comprising a petrol tank, carbureter with rotary drum pump and gas holder, the petrol supply device and drum pump being driven from a common shaft rotated by weights acting on a cord wound on 60 said shaft.

Fig. 2 is a detail sectional view on line 2—2 Fig. 3 showing the water overflow compartment and the means for returning the water to the main chamber.

Fig. 3 is a section on the line 1—1 of Fig. 2 looking in the direction of the arrow, with part of the partition wall broken away to show the water scoop behind.

Fig. 4 shows a modified arrangement.

I will now describe the general arrangement and operation of the apparatus shown in Fig. 1.

Upon a frame or stand *a* is mounted a closed casing *b* within which is arranged a 75 rotary drum pump *c*, the shaft *d* of which is carried in a thrust bearing *e* inside the casing, its outer end extending through a stuffing box *e'* and terminating in a bevel gear *e''*.

Upon the stand *a* is mounted a tank *f* for petrol or other volatile hydrocarbon in which rotates, fixed to a shaft *f'* a disk *f''* or spider, upon which are mounted a number of cups or buckets *f'''*, arranged so as to pick up charges of petrol, as they dip into the liquid in the tank *f*, and discharge their contents after they arrive at their highest position, on to a tray or gutter *f''''*, from whence the liquid passes into a pipe *f'''''* the other end 85 of which enters the top of the casing *b*. The petrol tank *f* is closed in an airtight manner by a cover *f''''''*, a petrol charging opening being provided, closed by a cap or stopper *f'''''''*.

90 Outside the tank *f* the shaft *f'* is provided with a pulley *f''*, over which passes a cord or chain *f'''* passing around a second pulley *f''''* mounted on a driving shaft *g* carried in bearings *g''* on the stand *a*.

100 On the shaft is also mounted a bevel wheel *g''* meshing with the bevel wheel *e''* on the pump shaft *d*.

The shaft *g* may be driven by a weight motor or in other convenient manner.

105 On the stand *a* a gas holder, comprising a vessel *h* with bell *h'* is mounted, an inlet pipe *j* for gas forming a communication be-

tween the interior of the drum pump *c* and the space beneath the bell *h'*. A gas outlet pipe *h* from the bell *h'* is provided with a union *h'* to which a pipe may be connected to lead the gas to the place of consumption.

10 A third pipe *l* extends upward into the tank *h* and is provided at the top with an opening or openings *l'* for air, the lower end of the pipe *l* communicating with the pump casing at *l''*. The pipe *l* also passes freely through the top of the bell, which is provided with a sleeve or lining adapted to close the opening or openings *l'* in the pipe *l* when the bell reaches its highest position.

15 The pipe *j* at its lower end is connected as by a *T* piece, with a branch pipe *j'* which extends upward so that its open top lies near the top of the drum pump extension *c'*. This extension is in the device illustrated of a conical form having a central opening *c''* forming a communication between the interior of the drum and the exterior space which exists between the outside of the pump and the interior of the casing.

20 25 The casing is provided with a partition *b'* (Figs. 2 and 3), which, except for certain openings, hereinafter referred to, completely shuts off the space *b''* from the space *b'''*. In this space or chamber *b'''* I arrange a disk *b⁴* carrying buckets *b⁵*, similar to the buckets in the petrol tank *f*, the disk being fast on the shaft *d*, so that it rotates therewith and with the pump *c*.

30 35 The partition *b'* is cut through just below the horizontal center line so as to form horizontal openings *b⁶* on either side of the vertical center of the partition. The material of the partition immediately below the horizontal cuts is bent outward at *b⁷* toward the bucket disk, and the material of the partition immediately above the cuts is pressed inward at *b⁸* two V-shaped side openings *b⁹* (Fig. 2) are thereby formed which are closed by side plates *b¹⁰* (Fig. 3). I thus 40 form pockets projecting from the face of the partition *b'*, which pockets form communicating spaces between the chambers *b''* and *b'''* at a height which represents the normal water level of the apparatus. An overflow 45 funnel *m* with pipe *m'* passing out through the bottom of the casing, and there provided with a tap *m''* (Fig. 1) is provided to test when the correct amount of water has been charged into the casing, an opening *b¹¹* being formed for the purpose in the partition *b'* communicating with the mouth of the funnel *m*. A lubricating pipe *n* is also provided to supply lubricant to the bearing of the shaft *d*.

50 55 60 The pump shown in the drawings consists of a hollow drum *o* closed at both ends, mounted upon the shaft *d*. Around this drum are formed a number of helical conduits *o'*, their outer openings or mouths *o''* lying radially around the front of the pump

and their inner ends or tails *o'''* opening similarly into the space *c''* within the extension *c'*.

It will now be understood that if the casing is charged with water up to the level 70 shown in the drawing and the drum pump is rotated in the direction of the arrow (Fig. 1), the mouths *o''*, as they rotate will scoop up gas and when they plunge into the water will compress said gas and force it 75 along the helical conduits until it issues at the other end of the drum, into the chamber *c''*.

The operation of the machine will now be described.

80 A suitable amount of petrol or other volatile fuel is charged into the tank *f*, sufficiently say to half fill it. Water is also introduced into the casing *b* until it reaches the level of the horizontal openings *b⁶* which 85 can be tested by turning on the tap *m''* (Fig. 1).

The drum pump is thus half immersed in water, which in addition to partly surrounding the pump also enters and partly 90 fills the space within the extension *c'*. There are consequently two spaces separated from each other by water *i. e.*, the space in the upper part of the casing around the pump drum, and the upper space inside the 95 casing *c'* into which the pipe *j'* extends.

The weight motor being brought into action acts upon the cord wound on the shaft *g* and slowly rotates it. This rotation is transmitted by the chain *f⁷* and bevel gear *g² e²* respectively to the petrol feed shaft *f⁵* and the drum pump *c*. Petrol is thus, as the shaft *f⁵* rotates, picked up by the buckets *f²* and discharged on to the channel *f³* from which it flows down the pipe *f⁴* into the casing *b* and drops on the outside of the pump, where it vaporizes and mixes with the air therein, this air entering the casing *b* through the pipe *l*. The pump being simultaneously rotated takes up this carbureted 105 air by means of its mouths *o''*, which successively plunges into the water thus causing the carbureted air taken up to be forced under pressure along the helical conduits 110 until it issues from the outlets *o'''* and rises 115 to the top of the space *c''* in the pump extension *c'*. From thence the gas passes down the pipe *j'* up the pipe *j* into the bell *h'*, from whence it is drawn off through the pipe *h'* in accordance with the required 120 consumption of gas, the bell rising or falling according to whether the supply or consumption of gas is the greater. When the bell is full, that is to say, in its highest position, the air-inlet *l'* is closed by the sleeve 125 on the bell, and consequently no more air can enter the casing *b*. The drum pump, continuing to revolve, will still draw off carbureted air from the space *b''* whereby a 130 partial vacuum will be formed and the

pump will therefore meet with gradually increasing resistance until the effect of the vacuum overcomes the effect of the weights and the machine will thus stop running automatically until further gas is drawn off and the air inlet b' uncovered, whereupon the vacuum will be destroyed and the pump will again commence to revolve. The petrol feed being driven synchronously with the pump, the amount of petrol feed will be in direct relation to the speed of rotation of the pump, and when the latter stops the petrol feed will also cease.

The apparatus is thus automatic in its action and when once started requires no attention, except periodical winding up of the weights of the motor, lubricating and recharging the petrol tank. The mixture of air and petrol is of substantially a constant value, when the gas consumption is steady, but when the consumption fluctuates by gas being drawn off irregularly, the constancy of the mixture would vary, since the level of the water in the casing b , and consequently the volume of the space b^2 in which the air is carbureted will vary in accordance with the pressure of the gas in the space c^3 , due to the weight of the bell and to the action of the pump as it forces carbureted air into the space c^3 , so that when the pressure exceeds the normal water from the space c^3 is forced out, by the gas pressure, into the outer space b^2 . It will be evident that unless the water level be maintained substantially constant, the richness of the gas mixture will vary, since given amounts of petrol will, at different times, be vaporized in different volumes of air.

To maintain a substantially constant water level, for the purpose of preventing variations in the gas pressure in the carburetor, due to any cause, I provide a water overflow space or chamber b^3 , in which rotary scoops b^5 pick up and return to the main casing b any water which is forced out of the latter by increase gas pressure, through slots or passages b^6 into the overflow space b^3 , the water picked up by the scoops being carried up and discharged after the scoops reach their highest position, and caught by the outwardly projecting strip b^7 on the water discharge side of the partition b' .

Thus almost simultaneously with the overflow of the water from b^2 it is returned thereto by the scoops b^5 , and a substantially constant level of water in the casing b is maintained.

The principle of the invention is capable of being carried out in a variety of ways. For instance, in the modification shown in Fig. 4, the casing b which may be arranged at an incline, as in Fig. 1, or horizontally is provided with a horizontal slot or slots b^6 formed by cutting and pressing out the part b^7 , so that the edge of this part is at the re-

quired normal water level. Attached to the side of the casing b is a narrow overflow tank B , provided with a spider or disk b^4 carrying buckets b^5 . The shaft b^{10} to which the disk b^4 is secured is carried in a bearing B' and is provided with a driving pulley B^2 . This shaft b^{10} is parallel with the driving shaft g by which the pump or the like is driven, so that, by extending the shaft g to the left and providing it with a pulley, opposite the pulley B^2 , the shaft b^{10} can be easily driven at the required speed suitable diameters of the pulleys being chosen for that purpose. The action is the same as in the previous construction, water, which is forced out of the casing b being picked up and returned thereto by the scoops b^5 .

What I claim and desire to secure by Letters Patent is:—

1. A carbureting apparatus comprising a water receptacle, a rotatory pump in said receptacle, means for supplying liquid hydrocarbon and air to be carbureted to said pump, a second receptacle adjacent to and communicating with the water receptacle by an opening at the normal water level to permit water to overflow into the second receptacle from the water receptacle when the water level therein exceeds the normal, means for returning the overflow water to the water receptacle, and an extension casing on the pump to receive the carbureted air from the latter and a draw-off pipe opening into the top of the extension casing, substantially as set forth. 100

2. A carbureting apparatus comprising a water receptacle, a rotatable pump drum in said receptacle, means for supplying the liquid hydrocarbon and air to be carbureted to said pump, a partitioned-off extension of said receptacle giving a water-overflow chamber, a water-level opening in the partition between the overflow chamber and the pump chamber to permit water to overflow into the second receptacle from the water receptacle when the water level therein exceeds the normal, means for returning overflow water to the pump chamber on the rotation of the pump, and an extension casing on the pump to receive the carbureted air from the latter and a draw-off pipe communicating with said extension chamber, substantially as set forth. 113

3. In a carburetor a pump chamber, a partition dividing the chamber into two separate chambers, a shaft extending through both chambers, a rotatory pump body mounted on said shaft in one of the chambers, an extension casing of the pump on one side, a draw-off pipe opening into the top of the extension casing, and a water-level opening in the partition between the pump chamber and the other chamber, and water scoops in the latter mounted on the shaft, substantially as set forth. 120

4. A carbureting apparatus comprising a water receptacle, a rotatory scoop pump comprising a series of helical conduits in said receptacle, means for supplying liquid hydrocarbon and air to be carbureted to said pump, a second receptacle communicating with the water receptacle by an opening at the normal water level to permit water to overflow into the second receptacle from the water receptacle when the water level therein exceeds the normal, means for returning the overflow water to the water receptacle, and an extension casing on the pump to receive the carbureted air from the latter and a draw-off pipe opening into the top of the extension casing, substantially as set forth.
5. A carbureting apparatus comprising a water receptacle, a rotatory pump in said receptacle, means for supplying liquid hydrocarbon and air to be carbureted to

said pump, a second receptacle communicating with the water receptacle by an opening at the normal water level to permit water to overflow into the second receptacle from the water receptacle when the water level therein exceeds the normal, means for returning the overflow water to the water receptacle, and an extension casing on the pump to keep the carbureted air issuing from the pump from mixing with the air in the water receptacle and a draw-off pipe for the carbureted air opening into the top of the extension casing, substantially as set forth.

In testimony whereof I have affixed my signature in presence of two witnesses.

FRITZ WILHELM OTTO BOECKEM.
